UNITED STATES PATENT OFFICE.

ALBIN STEINER, OF SONNEBERG, GERMANY.

SOUND-PRODUCING DEVICE FOR TOYS AND THE LIKE.

1,200,256.

Specification of Letters Patent.

Patented Oct. 3, 1916.

Application filed March 17, 1915. Serial No. 15,053.

To all whom it may concern:

Be it known that I, ALBIN STEINER, subject of the Duke of Saxe-Meiningen, residing at Sonneberg, Germany, have invented 5 certain new and useful Improvements in Sound-Producing Devices for Toys and the like, of which the following is a specification.

My invention relates to sound-producing 10 devices for toys and the like and more especially to the sort of devices actuated by bellows, and its particular object is a combination of bellows coacting in such a manner as to produce sounds as well on being 15 operated by hand as for some time after such operation has ceased.

With this object in view the device according to my invention consists of two bellows, one acting as an air compressor and 20 the other one as a sound producer actuated by said air compressor.

In the drawings affixed to this specification the preferred form of a sound producing device according to my invention is 25 shown.

Figure 1 is a vertical longitudinal section showing the sound producing bellows almost in the position of rest while the air compressing bellows is being operated to fill the 30 former with air. Fig. 2 is a vertical longitudinal section showing the sound producing bellows extended.

a is the sound producer, *b* is the compressor, *c* is its bottom-cheek, *d* is an air inlet in said bottom-cheek closed by an admission valve *f*.

g is the top-cheek of the compressor, *h* is an air outlet in the top-cheek closed by an exhaust valve *i* and allowing the air compressed within the bellows *b* to escape into an intermediate chamber *l* surrounded by walls *k* and serving to conduct the air to a hole *n* in the bottom-cheek *m* of the sound producing bellows *a*. The top-cheek *o* of said sound producing bellows is provided with a hole *p* leading to a small reed instrument or pipe *r* ending in a tube *q*. *t* is a compression spring tending to drive the top and bottom cheeks of the bellows *b* apart, *s* is a tension spring tending to draw the top and bottom cheeks of the bellows *a* toward each other.

By exerting pressure upon the top-cheek of the bellows *b* the spring *t* is compressed, 55 and upon the pressure being removed this spring will drive the top and bottom cheeks

asunder, thereby causing air to enter into the bellows *b* by the inlet *d*. Upon a renewed pressure being exerted upon the top-cheek of the bellows *b*, the air will escape through the outlet *h* into the intermediate chamber *l* and from there through the hole *n* into the bellows *a*, causing the spring *s* to be extended a little. By alternately compressing the bellows *b* and allowing the 60 spring *t* to drive its cheeks asunder the bellows *a* can be completely raised against the action of spring *s*. During this time, however, the weight of the top-cheek *o* of said bellows *a* as well as the tension of the spring *s* will exert a constant pressure upon the air 65 inclosed in said bellows and part of the air will constantly be expelled through the hole *p* and in passing through the instrument *r* will produce a more or less continuous sound. 70 The sound production will continue automatically after the pressure upon the bellows *b* has been discontinued and the bellows *a* have been completely filled with air, the weight of the top-cheek *o* together with 75 the tension of the spring *s* and of the leather or fabric side walls of the bellows causing the air introduced by aid of the bellows *b* to be slowly expelled through the hole *p* and the instrument *r*. This combination of bellows therefore affords a simple and effective 80 means for providing a toy such as for instance a human figure with a squealing or whining voice, the figure formed by surrounding the bellows with doll's clothes for 85 instance growing bigger at each pressure of the hand upon the top cheek *g* of the bellows *b* and squealing or screaming throughout the time the body is being inflated as well as after the pressure is discontinued, and 90 while the body is being contracted again.

I claim:

1. A sound producing device for toys comprising a bellows, a normally contracted expansible body having an inlet connected 100 with an outlet from the bellows, a wind instrument supported by said body and connected with an outlet therefrom, and means for preventing the passage of air from the body to the bellows, whereby the instrument 105 will be caused to sound while the body is being inflated and also while the bellows is inoperative and the body is contracting to its normal condition.

2. A sound producing device for toys comprising an expansible body, a wind instrument supported by the body and arranged 110

to be actuated by air escaping from an outlet therein, means acting to maintain the body in contracted condition, means for supplying air under pressure to the body, and means for preventing the return of air from the body to the inflating means, for the purpose described.

8. A sound producing device for toys comprising a bellows, an expansible body having an inlet connected with an outlet in the bellows, a wind instrument attached to the body and connected with an outlet therefrom, a spring acting to maintain the body in contracted condition, and means for preventing the passage of air from the body to the bellows, for the purpose described.

9. In a sound producing device for toys

and the like, in combination, a bellows, air inlet and outlet valves on said bellows, another bellows provided with an air inlet at one cheek and an air outlet and a wind instrument at the other cheek, an air-tight connection between the outlet valve of the first bellows and the air inlet of the second bellows, a spring adapted to keep the first bellows distended and a spring adapted to contract the second bellows.

In testimony whereof I affix my signature in presence of two witnesses.

ALBIN STEINER.
